UNITED STATES PATENT OFFICE.

CHARLES T. HASEMAN, OF MILL CITY, OREGON.

PULLEY BLOCK AND METHOD OF OPERATING PULLEY BLOCKS IN SKY-LINE SYSTEMS.

Application filed October 21, 1924. Serial No. 744,935.

My invention relates to pulley blocks and to the method of operating them in what is known in the art as sky line systems.

In sky line service a supporting carriage 5 is mounted high in the air upon a cable, of steel for instance, that is known as the sky line. Depending from said carriage a pulley block for hoisting a load, as of logs, towards the sky line preparatory to its transportation thereon is employed. In operative connection with the carriage and pulley block, respectively, lines for operating them from the ground are employed, for the reason that, when in service the carriage and block 10 are not conveniently accessible.

Sky lines as above described are devised for hoisting and carrying loads of such great weight as to require a corresponding exercise of power in the control and direction of the suspending elements and their load.

In consequence of the conditions that are developed in the practical operation of sky lines generally, a twisting effect upon the carriage, or upon the pulley block, or upon both the carriage and the pulley block is set up, which causes chafing of either the sky line, or the block-actuating line, or both of them, to a degree that is damaging to the apparatus, even to the point of danger to the workmen, and productive of serious loss in time and money.

The exposure to loss by reason of the twisting effect and its results above referred to has been recognized, and attempts have heretofore been made to remove the cause thereof, but with indifferent success.

My invention is designed and adapted substantially to eliminate the cause of the loss aforesaid, and to that end it comprises both improvements in the sky line system itself, in the method of operating pulley blocks therein, and also in the pulley blocks employed therein.

What constitutes my invention will be hereinafter specified in detail and succinctly defined in the appended claims.

In the accompanying drawings, in which my invention, in present preferred form of embodiment, is shown,

Figure I illustrates, largely in diagrammatic effect, a sky line system comprising my invention in respect both to the system and to the suspending elements, including the pulley blocks employed therein.

Figure II is a side elevation of one of my

two-sheave depending-blocks, detached, with portions of the pick-up-and-holding line shown therein as in use.

Figure III is a vertical section on the line III—III of Figure II.

Figure IV is a horizontal section on the line IV—IV of Figure II, showing deflection of the pick-up-and-holding line which occurs under tension at opposite ends of the two-sheave depending-block.

Figure V is a side elevation, complementary to Figure II, of one form, for example, of a suitable pick-up block.

Referring to the numerals on the drawings and in the first instance to Figure I thereof, 1 indicates, by way of example, a contour-line of the earth from which, as projecting on opposite sides of a canyon, are shown uprights 2 and 3, which, usually and as illustrated, consist of trees in place. Said uprights are connected, as at points indicated by the numerals 4 and 5, respectively, by a strong cable or sky line 6, and are, each in turn, braced by guys 7.

The sky line is of sufficient strength to carry the weight of the entire load which is suspended from it on a carriage 9 so as to travel upon the sky line between the uprights 2 and 3. The carriage shown in the drawings comprises a frame 10, having preferably a pair of grooved wheels 11, to fit the sky line, rotatively mounted between the cheek plates. The carriage may be of any suitable and preferred construction that is adapted to perform the office of a travelling carrier for the load.

Suspended from the carriage 9 by a universal joint loose means of connection, is a two-sheave depending-block 14. The loose manner of suspension thereof constitutes a feature of my invention, because by aid of it not only the block 14 but also the carriage is relieved of the injurious consequences of that twisting effect that is directly communicated to the block 14 and is indirectly communicated through it to the carriage upon the sky line 6, from which indirect effect, without adequate provision for preventing it, would result a seriously dangerous chafing of the line 6 against the frame of the carriage 9.

The universal joint loose means of connection aforesaid comprises preferably two links 15 and 16 united as in a chain. The link 15 makes pendulous union with the carriage frame 10 at a point below and substan-

tially equidistant from the wheels 11, if the preferred two wheels are used. The link 16 is by preference united to the frame of the block 14, substantially in the manner described in the paragraph next below.

The purpose of the block 14 is to effect antifriction means of reeving a line through it, so as to prevent abrasion between the block-frame and said line. The said means are 10 hereinafter described in detail. Towards the end in view said block frame comprises in effect two metallic side plates 17 and 18 of substantially corresponding suitable weight and dimensions, and preferably of 15 the general hexagonal shape, whose side elevation is well illustrated in Figure II. The plates 17 and 18 are united above with requisite strength and security, preferably by a yoke 19 secured between them as by 20 rivets 20, as shown in the drawings.

In like manner a spacing-block 21 is secured below between those portions of the plates 17 and 18 which are opposite to the yoke 19. The said yoke is loosely united to 25 the link 16 in some suitable way, as, for example, by a swivel joint 22 that is rotative about its vertical axis.

The space which separates the plates 17 and 18 is divided in two by a spaced median 30 plate 24, that is firmly anchored, above and below, in the yoke 19 and the spacing-block, respectively, and is provided with a suitable recess in its upper part for operative accommodation of the head 25 of the swivel joint 22.

In the spaces provided between the plates 17 and 18 and the parallel median plate 24, respectively, are, on adequately strong bearing pins 26, each fixed at one end in one of 40 said plates and at the other in the median plate 24, rotatably mounted, in suitable journal-bearing boxes 29, sheaves 27 and 28. The sheave 27 is disposed, at one end of the block frame, while the sheave 28 and its pin 26 is disposed at the other end of the block frame opposite to that in which the sheave 27 and its pin 26 are mounted.

The relative disposition of the sheaves 27 and 28, substantially as has been just described, is important for reasons which will 50 presently appear. In that connection also it should be again observed that the space between each side plate and the median plate is occupied only at one end by a sheave leaving the other end of said space empty; and that the two sheaves 27 and 28 are located at opposite ends, respectively, of the block 14. The feature of construction referred to in the last sentence will appear from careful comparison of the several Figures II, III, and IV of the drawings.

Relative to the disposition of the respective sheaves, it is next specified that each of the side plates 17 and 18, at the empty end 60 of the space defined as aforesaid between it

and the median plate 24, is provided with a recess whose shape, for example, is indicated by the irregular line 30 (compare Figures II, III, and IV). Said recess is provided for the operative accommodation of the 70 bearing faces of a group of three rollers, each group comprising a single roller 32 and a pair of parallel separated rollers 33, one of which groups is carried on the side-plate 17, and the other on the side-plate 18, the 75 respective groups being disposed at opposite ends of the block 14. The longitudinal axis of each roller 32 is disposed substantially at right angles to the longitudinal axes of its companion pair of rollers 33. Each roller 80 32 is preferably mounted on an axle 35 carried on its proper side-plate, 17 or 18, whichever it may be, in opposite bracket-supports 37, that are riveted to said side-plate.

Each one of each pair of rollers 33 is 85 mounted on a respective axle 38 of which the inner end is fixed to the median plate, and its outer end fixed to a bridge-plate 39 which spans the recess defined by the line 30 in its appropriate side-plate 17 or 18, to 90 which the opposite ends of the bridge-plate 39 is firmly secured as by riveting.

Each of the six several axles 35 and 38 is terminally threaded and provided with a 95 nut 40 adapted to hold the axle to which it is attached in place.

43 indicates a pick-up-and-holding line that is fixedly secured, as indicated at 44, to the upright 2, and which passes through a guide pulley 45 on the upright 3 to suitable 100 operating mechanism of ordinary kind not necessary to illustrate. The line 43 in passing between the uprights 2 and 3 includes a loop portion 46 which hangs below the block 14 from the sheaves 27 and 28 over 105 which the line 43 runs. The turns of the line 43 about the said sheaves, respectively, are made so as to effect an overlap of the line upon opposite sides of the median plate 24, which serves in that regard as a partition plate to keep the overlapping portions of the line 43 positively separated and out of contact. Also, the line 43 enters the 110 block 14 between one of the groups of rollers 32 and 33 and leaves it from between the other group of rollers, so that it is smoothly guided by cooperation of the two groups in its passage through said block.

By the relative disposition last described 115 of the sheaves in the block 14 with reference to the members 44 and 45 which define the stretch of the line 43 between the uprights 2 and 3, any dangerous result from the tendency of tension upon the line 43 to impart 120 twisting movement on its vertical axis to the block 14 may be reduced substantially to the point of elimination, through the cooperation of the respective groups of rollers 32 and 33 which effectually prevents any chafing of the line 43 at any point against the 130

frame of the block 14. The rollers 32 co-operate in that regard to smoothly guide the line 43 under lateral twisting tendency of the block 14, while the opposing rollers 33 of each roller group smoothly guide the line 43 against any tendency of the block 14 to tip up or down, in consequence, for example, of the pendulous motion which is imparted to it in use.

10 The function of the line 43 is operatively to support in its loop portion 46 a pick-up block 47 which may be of any suitable form, that illustrated being preferred because of its strength, simplicity, and economy of construction. The block 47 may comprise besides a single sheave 48 and a pendent clevis 49 to which a load 50 may be secured, eyelets 51 and 52 disposed, respectively, upon opposite sides of the block 47. Said eyelets 20 represent any suitable means for attaching to the block a main line 53 and a haul-back line 54, by aid whereof, through connection directly with the block 47, the carriage 9 and all the members pendent therefrom, including the block 47, may be caused to travel 25 along the sky line 6.

The lines 53 and 54 might be separate lines, but they preferably constitute two portions of one endless line 56 which is, as 30 by properly disposed guide pulleys 57, directed to suitable operating mechanism, not illustrated. Said operating mechanism is, of course, located within operative proximity to the mechanism above mentioned for operating the line 43, so that the two lines 43 and 56 may be, at a single convenient station, brought under the control of one operative.

35 The operation of the apparatus described in the foregoing specification may be briefly explained as follows.

Let it be assumed that the apparatus is installed for service as shown in Figure I, and that the pick-up block 47 has received 45 and lifted to the desired height above ground its load 50. Under such conditions the line 43 has, in its pick-up capacity under actuation by its operating mechanism, done its office.

50 Afterwards, being held by said mechanism under tension between its points of support 44 and 45, the line 43 functionates in its further capacity as a holding line, that is to say, it holds the block 47 and its load in 55 suspension in midair. The point of said suspension may be anywhere on the line 6 along which it is the purpose intended to transport it through travel upon it of the carriage 9. Said travel, in either direction from 60 the point of suspension illustrated in Figure I, may be effected through actuation by its

appropriate operating mechanism of the line 56 in the manner described below.

Let it be assumed, for instance, that the carriage is in travel towards the upright 3. 65 In that case a pull upon the line 53 will effect the result desired in the following manner.

Pull upon the line 53 will be exerted directly upon the block 47, which will, through the 70 strands of the loop portion 46 of the line 43, be transmitted to the block 14 and, through it, ultimately with motive effect to the carriage 9. The block 14, during the time of the exertion of said pull, will slide upon the 75 line 43 without disturbing its operative relationship already described, with respect to said block. While the line 53 is operating to draw the carriage 9 in the manner just described, the line 54 will be under tension 80 produced by the weight or frictional resistance to motion of the slack of the line 56 of which the lines 53 and 54 are parts, as has been previously specified. The effect produced will be a counter strain exerted 85 between the lines 53 and 54 which will tend, in great measure, to prevent pendulous vibration of the members depending from the carriage.

The slip of the line 43 through the block 90 14 will be smoothly facilitated by the cooperative guidance of the rollers 32 on opposite ends of said block, and said rollers will prevent abrasion between that block and the line 43. At the same time, the presence of 95 the loop portion 46 of the line 43 will permit in the block 14 more or less of an up and down swinging motion which the pairs of opposing rollers 33 will effectually take care of, so as to prevent abrasion between 100 the block 14 and its line 43 that might be, in the absence of the rollers 33, occasioned by the up and down swinging motion, aforesaid.

What I claim is:

1. In an apparatus of the class described, a block traversable along a cable, said cable being reeved through said block to exert a torsional influence thereupon, and anti-friction means on the block for engaging the 110 cable to resist said torsional influence.

2. In an apparatus of the class described, a block traversable along a cable, said cable being reeved through said block to exert a torsional influence thereupon, and fore and aft anti-friction means on said block for engaging the cable to resist said torsional influence. 115

In testimony whereof, I have hereunto set my hand.

CHARLES T. HASEMAN.
